UNITED STATES PATENT OFFICE.

THOMAS ZIMMERMAN, OF NIAGARA FALLS, NEW YORK, ASSIGNOR, BY MESNE ASSIGNMENTS, TO U. S. LIGHT & HEAT CORPORATION, OF NIAGARA FALLS, NEW YORK, A CORPORATION OF NEW YORK.

STARTER FOR ENGINES.

1,290,472.

Specification of Letters Patent.

Patented Jan. 7, 1919.

Application filed March 4, 1915. Serial No. 12,173.

To all whom it may concern:

Be it known that I, THOMAS ZIMMERMAN, a citizen of the United States, residing at Niagara Falls, in the county of Niagara and State of New York, have invented new and useful Improvements in Starters for Engines, of which the following is a full, clear, concise, and exact description, reference being had to the accompanying drawing, 10 forming a part of this specification.

This invention relates to starters for engines and with regard to certain more specific features thereof, to devices of such character having normally incomplete or 15 interruptable transmissions.

It is one of the objects of the present invention to provide reliable starting apparatus of such simplicity in number and arrangement of parts that the possibility of 20 disarrangement is reduced to a minimum and any developed "trouble" will readily be apparent to the lay operator.

Another object lies in the provision of means whereby the power transmission, and 25 other connections, may be easily and quickly effected.

Another object lies in the provision of a geared starter which is reliable, durable, and efficient in operation.

Still another object lies in the provision 30 of apparatus of the character described wherein the power transmission may be automatically interrupted upon the development of a certain speed of the engine, and 35 wherein the transmission may be readily and effectively recompleted without lost motion when the engine speed is below a certain value.

Other objects will be in part obvious and 40 in part pointed out hereinafter.

In the accompanying drawings wherein is shown one of the various possible embodiments of the invention—

Figure 1 is a view of the invention in side 45 elevation, with parts broken away to show more clearly the interior structure.

Fig. 2 is a section taken substantially along the line 2, 2, in Fig. 1.

Fig. 3 is a view in top plan of the transmission case and contents with the top cover 50 removed.

Fig. 4 is a diagrammatic view of the invention.

Fig. 5 is a view of the over-running clutch.

A frame or housing 1 incases the series field 2, the motor armature 3 and the power transmission devices, indicated generally by the numeral 4. The fly-wheel 5 is mounted for rotation with the crank shaft of an internal combustion engine (shown in Fig. 4). This fly-wheel is provided with an external gear 6, the teeth of which are adapted to mesh with the teeth of a pinion 7, mounted for rotation upon the splined shaft 8 and adapted to be shifted longitudinally of said shaft into and out of engagement with the gear 6. The shaft 8 has reduced ends 9 which are journaled in anti-frictional bearings 10 in the casing 1. Said shaft is adapted to rotate freely relatively to said casing 1, but is secured preferably against endwise movement therein. The body of the shaft 8 has a plurality of projections 11 which engage recesses 12 in the pinion 7. This construction provides a strong and durable connection between the shiftable pinion and the shaft and prevents stripping. The pinion 7 has a hub portion 13, preferably integral therewith, provided with an annular groove 14 and is straddled by a yoke 15 of a depending arm 16, for purposes which will be hereinafter set forth. Fixed on the shaft 8, adjacent the left wall of the casing 1, Fig. 1, is a clutch element 17, co-operatively associated with a second clutch element 18, which in turn is provided with external gear teeth 19, and these in turn mesh with the teeth of a pinion 20, fixed on the armature shaft 21. Suitable anti-friction bearings 22 are provided in the casing 1 for supporting the armature and permitting free rotation thereof. A lever 23 is pivotally mounted between ears 24, projecting from the casing 1, as indicated at 25. The lower end of this lever is pivotally connected with a rod 26 slidably mounted in a bushing 27 in the frame 1. This rod connects in some suitable manner with the arm 16 and is preferably threaded thereon as indicated at 28. A coiled expansile spring 29 surrounds the shaft 26 and a portion of the bushing 27 and bears against the upper end of the arm 16 to hold the pinion 7 normally out of engagement with the gear 6 of the fly-wheel. Near the top of the frame

or housing 1 there is slidably mounted a push-rod 30, having a bifurcated portion 31, which straddles the upper end 32 of the lever 23. This push-rod connects at 5 its outer end with any suitable foot or hand-operated member 33. A stud 34, connecting the walls 31 formed by the bifurcation of the push-rod, and an abutment 35 formed by the termination of the recess, are spaced 10 apart to provide a certain amount of lost motion between the push-rod 30 and the lever 23, when actuating the device to complete the transmission. A block 36 is mounted upon the push-rod as by a cotter 15 pin 37, and this block carries bridging members, 38, 39, for controlling the electrical circuit, as will be later described. A coil spring 40 surrounds the push-rod 30, bears indirectly against the block 36 and reacts 20 indirectly against the casing 1, tending primarily to maintain the bridging members 38 and 39 in open contact position, and secondly to coöperate with the spring 29 to maintain the pinion 7 out of engagement 25 with the gear 6 of the fly-wheel.

Depending from the removable cover 21, there are two pairs of contacts 42 and 43 respectively. The contacts 42 are adapted for engagement with the bridging member 30 38 upon initial movement of the push-rod 30, whereupon the electrical circuit between the storage battery 44, or other source of electrical energy, and the motor is completed through a resistance coil 45. Subsequent 35 movement of the push-rod 30 against the action of the spring 40, closes the electrical circuit across the contacts 43 by bringing the bridging member 39 into engagement therewith, and this cuts out the resistance 40 coil 45. Binding posts 46 and 47 are mounted on the removable transmission case cover 41 and are connected suitably with the contact pairs 42 and 43.

The operation of the device is as follows:

45 Assuming the parts to be in normally open position, as shown in Fig. 1, to start the engine, the operator presses the member 33, which in turn urges the push-rod 30 in a forward or inward direction against the action of the spring 40. To a certain point, this movement is comparatively easy, as the spring 40 is affording the only substantial resistance. The parts are arranged, however, so that an amplitude of travel, sufficient to engage the bridging member 38 with the contacts 42, simultaneously engages the stud 34 with the upper end 32 of the lever 23. At this time the circuit is complete from the battery 44 to the motor, but the 50 circuit includes the resistance coil 45 with the field and the latter is accordingly energized below its full normal value. This causes the motor armature to turn slowly. Accordingly the pinion 20 is set in motion 55 and transmits power to the clutch member

18, which in turn drives the clutch member 17 through a medium which will be described later. Rotary movement imparted to the clutch member 17 will, of course, rotate the shaft 8 and accordingly, the shiftable pinion 7. The construction just described overcomes the inertia of the transmission parts and affords a slow rotative 70 finding movement for the pinion 7, which, at this time, is slightly out of engagement 75 with the gear 6 of the flywheel. Upon further movement of the member 33 by the operator, the resistance of the spring 40 is increased, the action of the spring 29 and the inertia of several parts is added to the force 80 to be overcome by the operator. This has a tendency to create a two-step inward movement of the push-rod 30, the second step being retarded slightly because of the added resistance, permitting the motor to get well under way before the mechanical transmission is complete. The second step of the inward movement of the plunger 30 carries the bridging member 38 beyond the contacts 42, and the resisting force mentioned having been overcome at this point, the bridging member 39 is brought quickly 90 into engagement with the contacts 43. Also, during the second step of the push-rod, the stud 34 moves the lever 23 about its pivot 95 point 25 and acts through the slide rod 26 and yoke 15 to shift the pinion 7 along the shaft 8 into full engagement with the gear 6 of the fly-wheel. The mechanical transmission is completed at or about the time 100 that the bridging member 39 closes the electrical circuit across the contacts 43 and cuts out the resistance coil 45. Thereupon, the motor speeds up rapidly, and through the pinion 20, over-running clutch and shiftable 105 pinion 7, turns the fly-wheel 5 to cause the necessary compression in the engine cylinders. As soon as the engine commences to operate under its own power, the fly-wheel speed increases to such an extent that there 110 is a tendency to rotate the pinion 20 at a greater speed than that imparted to it by the speed of the armature. This automatically disconnects the clutch members 17 and 18 in the following manner:

115 By reference to Fig. 5, it will be seen that the over-running clutch device comprises the clutch member 17 and the clutch member 18 which are connected together by means of rollers 44' being wedged by the cam faces 120 45' on the clutch member 17, into engagement with the inner circumferential wall of the clutch member 18. It will be obvious that if the shaft 8 rotates at high speed and carries the clutch member 17 at a speed 125 greater than that which is imparted to the clutch member 18 by the motor, the rollers 44' will recede from their wedged position against the action of the springs 46' and thereby disconnect the two parts of the 130

clutch. When the speed of the shaft 8 becomes equal to or less than that of the clutch member 18, the springs 46' immediately restore the rollers to wedged position, 5 so that there is practically no lost motion.

As many changes could be made in the above construction and many apparently widely different embodiments of this invention could be made without departing from 10 the scope thereof, it is intended that all matter contained in the above description, or shown in the accompanying drawings, shall be interpreted as illustrative and not in a limiting sense.

15 It is also to be understood that the language used in the following claims is intended to cover all generic and specific features of the invention herein described, and all statements of the scope of the invention 20 which as a matter of language might be said to fall therebetween.

I claim—

1. In engine starting apparatus, in combination, an internal combustion engine, an 25 electric motor, a source of electricity, a unitary switching means movable at the option of the operator for establishing connection between said source and said motor, said switching means having an off position 30 and two distinct operative positions and driving connections between said motor and said engine, the operativeness of said connections being dependent upon the position of said switching means, said switching 35 means being biased by a plurality of springs dividing the movement thereof into two distinct steps.

2. In engine starting apparatus, in combination, an internal combustion engine, an 40 electric motor, means adapted to energize said motor, power transmitting devices between said motor and said engine, and resistance controlling means coöperating with the first said means adapted primarily to 45 give the motor a slow starting movement and to cut out said resistance to increase the speed of said motor when the transmission is established, said resistance controlling means being biased by a plurality of springs 50 dividing the movement into two distinct steps.

3. In engine starting apparatus, in combination, an internal combustion engine, an electric motor, means adapted to energize 55 said motor, power transmitting devices between said motor and said engine, resistance controlling means coöperating with the first said means adapted primarily to give the motor a slow starting movement and to cut 60 out said resistance to increase the speed of said motor when the transmission is established, and means adapted automatically to render said power transmitting devices ineffective when said engine is self-actuated, 65 said resistance controlling means being

biased by a plurality of springs dividing the movement into two distinct steps.

4. In engine starting apparatus, in combination, an internal combustion engine, an electric motor, power transmission devices 70 between said engine and said motor, a source of electrical energy, and a unitary switch means connected between said source and said motor said switch means having an off position and two distinct operative positions 75 whereby the voltage at the motor terminals may be selectively varied, said switch means being biased by a plurality of springs dividing the movement thereof into two distinct steps corresponding to said two 80 operative positions.

5. In engine starting apparatus, in combination, an internal combustion engine, a series motor, power transmission devices between said engine and said motor, a source 85 of electrical energy, a resistance between said source and said motor, a switch having two distinct stages of operation, one of which cuts said resistance out of circuit and a member adapted to be manually operated 90 for moving said switch and also operatively connecting said power transmission devices, said member being biased by a plurality of springs dividing the movement thereof into two distinct steps corresponding to said two 95 stages.

6. In engine starting apparatus, in combination, a source of electrical energy, a motor arranged to be operated from said source and having connected therewith a power transmitting member, a resistance in 100 circuit between said source and said motor, a switch adapted in one operative position to connect said source to said motor through said resistance and to simultaneously move 105 said power transmitting member independently of the action of said motor and in another position to cut out said resistance, said switch being biased to divide the movement thereof into two distinct steps corresponding to the said two positions thereof.

7. In engine starting apparatus, in combination, a source of electrical energy, a motor arranged to be operated from said source and having connected therewith a power transmitting member, a resistance in 115 the field circuit of said motor, a circuit controlling switch, a device adapted to control movement of said power transmitting member, and means manually operable whereby 120 said switch may be moved to first establish an operative electrical circuit through said resistance and maintain the same while moving said member and subsequently to cut out said resistance, said switch being biased to 125 divide the movement thereof into two distinct steps.

8. In engine starting apparatus, in combination, an internal combustion engine having a power transmitting member, a source 130

- of electrical energy, a motor arranged to be operated from said source and having connected therewith a power transmitting member adapted to be coöperatively associated with the member of said engine, a 5 resistance in the field circuit of said motor, a circuit controlling switch, a device adapted to control movement of said power transmitting member, and means manually operable 10 whereby said switch may be moved to first establish an operative electrical circuit through said resistance and maintain the same while moving said member and subsequently to cut out said resistance, said 15 switch being biased to divide the movement thereof into two distinct steps.
9. In engine starting apparatus, in combination, a source of electrical energy, a motor arranged to be operated from said 20 source and having connected therewith a power transmitting member, means adapted to be manually operated for causing a relatively low speed of rotation of said motor and in the same movement, causing movement 25 of said member independently of the action of said motor, and means whereby said member may move at a greater rotative speed than the speed derived from the motor armature, said manually operated means being biased to divide the movement thereof 30 into two distinct steps.
10. In engine starting apparatus, in combination, an internal combustion engine having a power transmitting member, a source 35 of electrical energy, a motor arranged to be operated from said source and having a power transmitting member coöperatively associated with the member of said engine, means adapted to be manually operated for 40 causing relatively slow rotation of the motor and, in the same movement, causing independent movement of said member and subsequently causing a faster rotation of said motor, said means being biased by a plurality of springs dividing the movement 45 thereof into two distinct steps.
11. In engine starting apparatus, in combination, a storage battery, a series field motor arranged in an electrical circuit with 50 said battery, a switch for controlling said
- circuit through a cut-out resistance, a shiftable gear driven from the motor shaft, and means comprising a manually operable member for effecting movement conjointly of said switch and said gear, said means being biased by a plurality of springs dividing the movement thereof into two distinct steps.
12. In engine starting apparatus, in combination, a storage battery, a series field 60 motor arranged in an electrical circuit with said battery, a switch for controlling said circuit through a cut-out resistance, a shiftable gear driven from the motor shaft, means comprising a manually operable member for 65 effecting movement conjointly of said switch and said gear, and means permitting said gear to travel at a greater rotative speed than that of the motor armature, said switch being biased to divide the movement 70 thereof into two distinct steps.
13. In engine starting apparatus, in combination, a motor, a shiftable gear driven therefrom, a resistance in the field circuit of the motor, and means comprising a common 75 operating member whereby said resistance may be included in the field circuit of said motor, the gear may be shifted to operative power transmitting position and said resistance may be excluded from the field circuit, 80 said means being biased to divide the movement thereof into two distinct steps.
14. In engine starting apparatus, in combination, a motor, a shiftable gear driven therefrom, a resistance in the field circuit of 85 the motor, and means whereby movement of said gear toward operative power transmitting position simultaneously includes said resistance in the field circuit of said motor and said resistance is cut out upon a pre-determined attained position of said gear, 90 said means being biased to divide the movement thereof into two distinct steps.
- In witness whereof, I have hereunto subscribed my name in the presence of two witnesses. 95

THOMAS ZIMMERMAN.
